UNITED STATES PATENT OFFICE.

HARRY G. JENNISON, OF TOLEDO, OHIO.

WOOD IMPREGNATION.

1,237,521.

Specification of Letters Patent. Patented Aug. 21, 1917.

Application filed May 20, 1915. Serial No. 29,259.

To all whom it may concern:

Be it known that I, HARRY G. JENNISON, a citizen of the United States, residing at Toledo, Lucas county, Ohio, have invented 5 a new and useful Wood Impregnation, of which the following is a specification.

This invention relates to the treatment of porous material, especially as to coating the cell walls thereof.

10 This invention has utility when incorporated for asepticizing wood, especially piles and paving blocks.

Referring to the drawings:

Figure 1 is an enlarged section of porous 15 material; transversely of the extent of the cells therein;

Fig. 2 is an enlarged section of porous material, longitudinally of the extent of the cells therein;

20 Fig. 3 is a view similar to Fig. 1, with a portion of the cells fully charged or filled with impregnating substance;

Fig. 4 is a view similar to Fig. 2 showing full charging superficially, or coating extending along the cells;

Fig. 5 is a view similar to Fig. 1 showing the cell wall painting or coating effected by dispersing a superficial full charge throughout the material;

30 Fig. 6 is a view similar to Fig. 2 showing uniform distribution by air pressure action of the fractional full charge of impregnating substance of waterproofing solution throughout the material; and

35 Fig. 7 is a piece of timber or paving block of the asepticized material.

Considering as an instance of porous material the wood block 1, it comprises the rapid growth or open cells 2 and the slower 40 growth or smaller cells 3, usually alternating as the former for spring and the latter for summer or drier season growing.

Noting this variation in a single block of wood, and having also to contend with the 45 variations in cell size in different pieces of timber, it may be desirable in some instances to take steps to bring the batch of material for a single treatment to a measure of uniformity. To this end the material may be 50 placed in a vessel and subjected to steam pressure of say from ten to thirty pounds, depending upon the moisture content and thickness of the timber. The moisture content is thus equalized, and by then shutting off the steam and pulling a vacuum of twenty to twenty-six inches of mercury

column, the warmed timber tends to give up its excess moisture.

With the charge of material still in the vessel and the vacuum released, it may now be submerged in an impregnating solution 60 or asepticizing liquor, say for waterproofing purposes, a hydrocarbon or hot heavy tar product. Hydraulic pressure may be applied by forcing substance into the vessel while keeping the material submerged in the 65 impregnating substance 4 to fully charge or fill the cells adjacent the exposed faces of the material (Figs. 3, 4). In this treatment the material is densely coated or superficially fully charged with the tar 4.

70 The hydraulic pressure may be released and the surplus preservative liquor drawn off to leave the material now coated but un-submerged as to the impregnating substance. The coating or impregnating may be gaged 75 as desired as to duration and amount of substance charged. For coal tar or oil in long leaf yellow pine timber in three inch lengths longitudinally of the cells, a 125 pound pressure for two hours has been 80 found to suffice. Wood so treated as to coating or impregnating, may now be subjected to a fluid or air pressure sufficient to diffuse the oil throughout the timber for say one and one half hours. This gaseous or 85 pneumatic pressure in excess of the impregnating pressure has a dispersing action upon the impregnating substance, distributing it throughout the material to paint and fully coat the cell walls 5, 6 (Figs. 5, 6), while 90 leaving the cells open.

Upon release of this gas pressure in the vessel, the expanding air in escaping from the wood exudes therefrom any cell filling excess of impregnating substance, leaving 95 the timber 7 fully charged as coating its cell walls only. With these cell walls fully waterproofed or asepticized, they are fortified to resist weathering attacks. Moisture entering the cells and discharging therefrom 100 need not affect the wood, if the walls do not drink up such moisture. With the walls not drinking up the moisture, the wood is not expanding with moisture and shrinking upon drying out. Furthermore, there is not the 105 objectionable oozing out of impregnating substance from fully charged superficial cells, but the wood is fully treated at a minimum of expense in the volume of impregnating substance.

110 In the production of wood pavements from

blocks as treated herein, there is absence of any objectionable oozings or other deterrent conditions, even in the early use, and this without detracting from the permanence of 5 the pavement in resisting decay, and with a structure which stays in shape as initially laid.

In the subjecting to air pressure for diffusion of oil throughout the timber or paving blocks, this pressure may be so run up 10 as to seemingly slip past the oil in the cells of the wood, so that upon the completion of this step and removal of the air pressure, the excess liquid for painting the cells is 15 pressed from the timber.

What is claimed and it is desired to secure by Letters Patent is:

1. The method of distributing a superficially dense coating throughout the mass of 20 a porous substance embodying the filling of the outer pores with the impregnation material in excess of the coating requirements of the pores of the substance, dissipating such material throughout the pores of the unsub- 25 merged substance and eliminating the surplus of such material by the application of a gaseous pressure, and the release of such pressure to exude the surplus of such material from the substance.
2. The method of coating the cell walls of 30 wood embodying uniformly moistening the

wood by steaming, superficially fully charging the wood with impregnating substance by hydraulic pressure in excess of a quantity for coating the cell walls of the wood, 35 dissipating such impregnating substance throughout the unsubmerged wood by subjecting to a gaseous pressure and then removing the excess of the impregnating substance from the wood by increasing such gaseous 40 pressure, and releasing the pressure to effect exuding of surplus of the substance from the wood.

3. The method of expressing cell filling impregnating substance from porous mate- 45 rial including submerging the material at atmospheric pressure, applying hydraulic pressure to impregnate the submerged material, releasing such pressure, drawing off the excess impregnating substance to leave the ma- 50 terial unsubmerged, dissipating the impregnating substance throughout the material by gaseous pressure, and removing the surplusage of impregnating substance from the ma- 55 terial by forcing the gas to a penetration in the material, and releasing the pressure to cause the escaping gas to exude the impregnating substance from the material.

In testimony whereof I hereunto affix my signature.

HARRY G. JENNISON.
